UNITED STATES PATENT OFFICE.

FRANCIS WILLIAMS, OF ADELAIDE, SOUTH AUSTRALIA, AUSTRALIA.

RACK-EVAPORATOR.

1,388,152.

Specification of Letters Patent. Patented Aug. 16, 1921.

Application filed February 25, 1921. Serial No. 447,871.

To all whom it may concern:

Be it known that I, FRANCIS WILLIAMS, a subject of the King of Great Britain and Ireland, residing at C. B. S. Building, 90 5 King William street, Adelaide, State of South Australia, Commonwealth of Australia, have invented a certain new and useful Improved Rack-Evaporator, (for which I have obtained a patent in Australia, No. 10 14,235, Feb. 3, 1920,) of which the following is a specification.

This invention relates to an improved evaporator, of the type known as rack evaporators, and it has been specially devised in 15 order to provide an evaporator with which the drying process may be effectively and expeditiously completed in one building. And further, although this improved rack evaporator has been particularly devised 20 for drying fruits, it may be readily adapted to treat other materials such as, for instance, timber, skins, fibrous sheets and bricks.

This improved rack evaporator comprises, in combination a preparing room, sulfur 25 chambers, a wilting room and an evaporator chamber all arranged within a building of special construction, a set or sets of racks also of special construction adapted to be traveled through the several rooms and 30 chambers, and supports for such racks.

The building has a cover or roof that is supported upon posts arranged in transverse pairs in rows longitudinally of the building. There is a set or tier of racks between each 35 35 row of pairs of posts, and each post carries a number of rollers, one for each rack, upon which the racks may be traveled.

Each rack has a frame comprising longitudinal side members, of wood or metal, connected by transverse members at convenient intervals corresponding with the width of the evaporator chamber and reinforced by longitudinal and diagonal wires. The frame is covered with netting, or hessian, or wood 40 45 to support the materials to be dried.

The racks may be of any convenient length; there may be any number of racks in a set or tier and any number of sets of racks may be used according to the quantity 50 of material to be treated.

But in order that the invention may be more readily carried into practical effect it

will now be described with reference to the accompanying drawings in which—

Figure 1 is a diagrammatic plan of an 55 evaporator building according to this invention while

Figs. 2 and 3 are diagrammatic longitudinal and transverse sections thereof respectively, Fig. 3 being on a slightly larger scale 60 than Figs. 1, and 2.

Fig. 4 is a plan of a rack frame partly covered with netting.

Figs. 5 and 6 are detail end and side elevations respectively showing portions of one 65 construction of racks, and their supports while

Figs. 7 and 8 are similar views of a modification of such construction.

Fig. 9 is a transverse section of a rack 70 with wooden longitudinals.

Fig. 10 is a detail view showing the method of joining the sections of metal longitudinals of the rack.

The evaporating chamber and the wilting 75 room are situated side by side medially longitudinally of the building and extend from the front to the back thereof;—the preparing room 1 is outwardly of the evaporating chamber 2, and the sulfuring chambers 3 80 are outwardly of the wilting room 4.

The supporting posts 5 may be of wood or metal and they are arranged in transverse pairs in rows longitudinally of the building. There is sufficient room between each of the 85 posts of a pair to accommodate a set or tier of racks 6 while there is sufficient room between each pair of rows to enable the racks to be readily loaded and cleared.

Each rack 6 is supported on wheels or 90 rollers 7 arranged in opposed pairs on the pairs of posts 5. These wheels are preferably flanged as at 8 and they are carried on pins 9 protruding from brackets 10 that are secured to the posts 5 by bolts 11. The racks 95 may be of any desired length.

Each rack has a frame comprising longitudinal members 12 extending the full length of the rack and transverse members 13 secured thereto at regular intervals. Longitudinal stay wires 14 and diagonal wires 15 complete and reinforce the frame.

The side members 12 may be of wood as shown in Figs. 5, 6 and 9 or they may be of

metal piping as shown in Figs. 7 and 8. In the latter construction the sections of piping 16 are joined together by screw threaded plugs 17 so that the pipes present a continuous surface to the supporting rollers 7.

The rack frame is provided with a covering of wire netting or hessian 18 or with a wooden floor 19. It has been found that a metal frame covered with wire netting or hessian is most suitable for vine fruits and that a wooden frame with a wooden floor is most suitable for stone fruits.

Each rack or set of racks is adapted to be traveled longitudinally of the building 15 through the various rooms and compartments by suitable mechanism, not shown in the drawings.

When treating vine fruits or berries on racks covered with netting the bottom rack 20 will be supported a convenient distance from the floor to permit the insertion of a tray or trays to catch any berries that may fall from the racks.

When it is desired to treat materials or 25 products other than fruit the distance between the racks will be varied according to the material to be treated and it may be advisable, in some cases, to substitute wheeled trucks supported on rails for the 30 racks and rollers.

The evaporating chamber 2 and the wilting room 4 may be heated in any convenient manner. As illustrated there is a furnace 20 under the forward part of the chamber 2, 35 the gases from which furnace pass through flues 21 and 22 to sets of vertical tubes or pipes 23 in the chamber 2 and the room 4. These sets of pipes 23 lead through radiator boxes 24 to outlet flues 25. Fans 26 draw the heated air through the chamber 2 and the air current is deflected by a baffle 27 into the room 4 which may have fans 26^a at its forward end if desired. The sulfur 40 chambers 3 have pits 28 in which sulfur is burned the fumes being directed therefrom into the chambers.

Adjustable curtains such as 29 or doors or the like are provided between the rooms and chambers and further the rooms and 50 chambers may be divided into sections. In order to confine the fumes or heated air to the area under treatment each rack has transverse slats or ribs 30 secured to its floor and each slat carries on its upper edge a 55 flexible flap 31 of leather or the like that is adapted to contact with the transverse frame members 13 of the rack above it in the set.

Sweat bins 32 for storing the dried fruits 60 may be provided in the upper part of the evaporating chamber and beneath the roof, and elevators for raising the fruit thereto and outlet doors for removing it may be provided.

65 The parts described form a complete fac-

tory building with preparing room 1 (the racks 6 forming the preparing tables) sulfurizing chambers 3, wilting room 4 and evaporating chamber 2. The preparing room is also the clearing off room, and the 70 sweating floor or bins 32 complete the plant.

It is to be understood that the wilting room is for the purpose of wilting the fruit prior to passing it into the evaporating 75 chamber.

In describing the carrying of the invention into effect it will be described as with a single rack since each rack may be operated independently but the number of 80 racks in a set or tier and the number of sets of racks will be as required.

In operation the empty rack 6 is drawn into the preparing room 1 and loaded with fruit. It is then passed through the evaporating chamber 2 and the wilting room 4 into the sulfurizing chamber 3.

If the fruit is to be sulfured the doors at the ends of the chambers 3 are closed and the necessary quantity of sulfur burnt with 90 in the pits 28, the fumes therefrom passing into the sulfurizing chamber 3.

After this treatment the rack 6 is drawn back and its first section positioned within the evaporating chamber 2, the second sec- 95 tion being within the wilting room 4.

After the fruit upon the section within the evaporating chamber 2 has been dried sufficiently the rack 6 is again moved the first section being moved into the cleaning 100 off room and the section which was previously in the wilting room 4 being moved into the evaporating chamber 2, a third section being moved into the wilting room.

After treatment of the second section 105 within the evaporating chamber 2 the rack 6 is again moved bringing other sections into the evaporating chamber 2 and the wilting room 4, and this process is continued until the whole length of the rack has 110 passed into and through the evaporating chamber 2 and the treated fruit has been removed.

The rack is again loaded with fresh fruit, passed back through the evaporating chamber 115 and wilting room into the sulfurizing chamber and the operation is repeated.

Prior to and after each movement of the rack 6 the various curtains or doors along the sides of the evaporating room 2 are 120 opened and closed to permit of such movement.

What I claim is:—

1. An evaporator, comprising a preparing room, an evaporating chamber, a wilting room, and sulfurizing chambers, the chambers and rooms being provided with aligned tray supports to permit trays to be passed from one to the other.

2. An evaporator, comprising a preparing

- room, an evaporating chamber, a wilting room, and sulfuring chambers, the evaporating chamber and wilting room being side by side and between the preparing room 5 and sulfuring chambers, the chambers and rooms being provided with aligned tray supports to permit trays to be passed from one to the other.
3. An evaporator, comprising a preparing room, an evaporating chamber, a wilting room, sulfuring chambers, the chambers and rooms being provided with a plurality of aligned rows of tray supports, and a plurality of slidable trays on said supports.
- 15 4. In an evaporator, a plurality of compartments, a number of posts arranged in pairs transversely and in rows longitudinally in the several compartments:—sets or tiers of racks between each row of pairs of 20 posts, and rollers on the posts to support the racks and allow them to be traveled longitudinally.
5. In an evaporator:—an evaporating room provided with a heating system and 25 having a number of posts arranged in rows and in pairs and carrying rollers upon which a number of racks are supported and traversed into and through the evaporating room, the sides of said room being open but 30 fitted with curtains or doors of canvas, sheet metal or wood that may be adjusted to close the openings between the top of the room and the uppermost rack for the time being, as and when required.
6. In an evaporator:—a number of racks 35 each of which comprises two side bars of either metal or wood, running the full length of the rack, transverse pieces fastened thereto at intervals forming sections, longitudinal and diagonal straining wires, and a 40 covering of foraminous material.
7. In an evaporator:—a number of racks each of which comprises two side bars made up of lengths of metal pipe joined together by screw threaded plugs, cross pieces fastened to the said side bars at intervals 45 dividing the rack into sections, each of which sections is provided with stout straining wires and with a suitable covering.
8. In an evaporator having a number of 50 racks each of which comprises longitudinal members, transverse members secured thereto at intervals, longitudinal and diagonal straining wires and a covering or floor, slats secured to the floor of each rack at intervals 55 corresponding to the transverse members and flexible strips secured to the edge of each slat adapted to contact with the transverse members of the rack next above in the set or tier.
- 60 In testimony that I claim the foregoing as my invention I have signed my name in the presence of two subscribing witnesses this 18th day of January 1921.

FRANCIS WILLIAMS.
